CLAIM

The ornamental design for a satellite dish cover, as shown and described above.

DESCRIPTION

FIG. 1 is a front perspective view of a satellite dish cover showing my new design;

FIG. 2 is a left side elevation view thereof, the right side view being a mirror image thereof;

FIG. 3 is a front elevation view thereof;

FIG. 4 is a rear elevation view thereof; and,

FIG. 5 is a top plan view thereof.

The broken line showing of a satellite dish antenna, stars, and stripes illustrates environment only and forms no part of the claimed design.
